FIG. 4.

FIG. 5.

FIG. 6.

Inventor
W. G. Probst.

By *John Murphy Jr.*
Attorney

UNITED STATES PATENT OFFICE.

WILLIAM G. PROBST, OF LOUISVILLE, KENTUCKY.

ELECTRIC ENAMELING TOOL.

Application filed January 28, 1922. Serial No. 532,523.

To all whom it may concern:

Be it known that I, WILLIAM G. PROBST, a citizen of the United States, residing at Louisville, in the county of Jefferson and State of Kentucky, have invented certain new and useful Improvements in Electric Enameling Tools; and I do hereby declare the following to be a full, clear, and exact description of the invention, such as will enable others skilled in the art to which it appertains to make and use the same.

The invention relates to enameling tools and has for its object the provision of an electric tool for the purpose stated, which is light, safe and economical and which is compact and readily accessible in every part for inspection, replacement or other required purpose.

Other objects and advantages will be apparent and suggest themselves as the nature of the invention is understood.

While the drawings illustrate an embodiment of the invention, it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a side view of an electric enameling tool embodying the invention,

Figure 2 is a reverse view of the tool, showing the same on a larger scale and having the covering plate of the switch housing removed,

Figure 3 is a detail perspective view of a portion of the switch assembly, the parts being separated and disposed in a group,

Figure 4 is a central longitudinal section, the vibrating mechanism being in elevation,

Figure 5 is a transverse section on the line 5—5 of Figure 4, looking in the direction of the arrows and showing the parts on a larger scale,

Figure 6 is an enlarged end view of the tool, and

Figure 7 is a detail perspective view of the core, the parts being separated.

Corresponding and like parts are referred to in the following description and designated in the several views of the drawings by like reference characters.

The tool comprises a frame or hollow casting including a head 1, a handle 2 and an

intermediate neck 3 or housing for the switch mechanism. These parts preferably are of integral formation and consist of light casting of aluminum or other metal. An electric vibrating mechanism 4, of any approved construction and make, is disposed within the head portion 1 of the casing and is adapted to be operated by an electric current derived from any suitable source by means of an electric cord 5 or other well known form of conductor adapted to be coupled to a socket or other outlet in a manner well understood.

A core of insulating material is enclosed within the handle 2 and comprises a main section 6 and a supplemental section 7, the two sections when assembled being secured by suitable fastening means in any preferred way. Two contacts 8 and 9 are carried by the core and are preferably attached to the main section 6. The contact 9 has one terminal of the helix of the electric vibrator 4 connected thereto and a wire or conductor 10 has the other terminal of the helix connected thereto. A wire or conductor 11 is connected to the contact 8 and both wires or conductors 10 and 11 terminate in coupling ends 12 which admit of the wires of the electric cord 5 being coupled thereto. A plug 13, at one end of the electric cord 5, is adapted to be clamped to the handle 2 of the frame or casing by means of a nut 14 which is threaded to the end of the handle, said plug having an outer flange 15 which is clamped between the end of the nut 14 and the end of the handle 2. The wires of the electric cord 5 terminate in coupling ends which are carried by the plug 13 and are adapted to engage the coupling ends 12 whereby the connection is completed when the parts are properly assembled, as indicated most clearly in Figure 4.

The switch includes a circuit closing member 16 which consists of a plate or strip of metal of a length to engage both of the contacts 8 and 9. The part 16 is clamped between two elements 17 and 18 of insulating material and mounted upon a stem 19 which has a threaded portion 20 upon which the parts 16, 17 and 18 are mounted and made secure by a clamp nut 21. The stem 19 has a reduced end portion 22 which receives an expandable helical spring 23 which is confined between the nut 21 and a hollow nut 24 threaded into an edge portion of the part 3 of the frame or casing. The tension of the

spring 23 may be regulated by adjusting the hollow nut 24. The stem 19 extends through the opposite edge portion of the part 3 and is adapted to be engaged by means of a lever 25 pivoted at 26 and disposed in a recess 27 formed in the outer side of the part 3. The projecting end portion of the lever 25 extends along a side of the handle 2 and is spaced therefrom to be operated by pressure 10 of the hand for closing the circuit when the tool is in operation for supplying the material to the surface to be enameled.

The outer or front end of the frame or casing 1 is closed by means of a plate 28 which is bolted or otherwise secured thereto. This plate 28 carries the electric vibrating mechanism 4. A threaded collar 29 is attached to the plate 28 and the sieve (not shown) or other part carrying the enameling material to be distributed is adapted to be coupled to the tool by means of the collar 29. The collar 29 is provided with a base 30 which is secured to the plate 28 by means of machine screws or other suitable fastening 25 means.

A side of the housing 3 is open, whereby access to the switch mechanism may be had with the greatest convenience. A plate 31 closes the open side of the housing 3 and is retained in place by machine screws or bolts 32. The core, carrying the contacts 8 and 9 and the wires 10 and 11, is insertable into the handle 2 and removable therefrom through the outer end and is retained in 35 place by means of a nut 14 and the stem 19, the latter passing transversely therethrough.

When the tool is in operation, it is grasped by means of the handle 2 and the switch operating lever 25 is adapted to be actuated 40 either by tightening the grip or by applying pressure thereto by means of the thumb. In either event, inward movement of the outer end of the lever 25 moves the stem 19 inward

against the tension of the spring 23 and closes the circuit by bringing the member 16 45 into engagement with the contacts 8 and 9. When the pressure is removed from the outer end of the lever 25, the stem 19 is moved outward by means of the spring 23, thereby breaking the circuit and stopping the action 50 of the vibrating mechanism 4, whereby the supply of enameling material is cut off since the vibrating action of the container ceases. It will thus be understood that the service of the tool may be continuous or brief as required, according to the manipulation of 55 the switch lever 25.

What is claimed is:

An enameling tool consisting of a one-piece casing, said casing having a hollow 60 tubular handle, a conductor-means securing nut externally threaded on one end of said handle, the casing being increased in thickness at the other end of the handle to provide an outwardly disposed shoulder and to 65 form a neck, said nut and shoulder providing abutments for the hand, said neck having an exterior longitudinally extending recess, a switch carried by said neck having an operating member disposed in said recess 70 and extending rearwardly and having its gripping portion disposed intermediate said nut and shoulder so that it is engageable and operable by the same hand which grasps the handle, a hollow head integral with and of 75 greater diameter than the neck extending from the neck, a vibrating mechanism in the head, the outer end of said head being open, and a sieve-mounting plate closing said end.

In testimony whereof I affix my signature 80 in presence of two witnesses.

WILLIAM G. PROBST.
